CLAIM

I claim the ornamental design for a faceplate for electric power distribution equipment, as shown and described.

DESCRIPTION

3.1 is a front view of a faceplate for electric power distribution equipment showing the new design; and

3.2 is a perspective front, side, and top view thereof.

Lightly shaded portions of reproductions 3.1 and 3.2 are for the purpose of illustrating portions of electric power distribution equipment behind the faceplate that form no part of the claimed design.
